HORSE AND PONY HARNESS

Albert C. Buehler, 88 Hawly Woods, Barrington, Ill.
Filed July 15, 1960, Ser. No. 43,066
3 Claims. (Cl. 54—78)

The invention relates generally to harness means for horses and ponies, and more particularly to means for improving their appearance with respect to the form and apparent position of their tails when they are on display or in competitive judging shows.

There are a large number of factors upon which the professional or experienced judge of horses and ponies bases his opinion for the winner in a show or contest. Among these are the general proportions of the pony, that is, overall length to height, stance, the condition of the hair, relative size of muscles, condition of the mouth and teeth, normal position of the ears, and numerous other factors which in the opinion of the expert add grace, beauty, and value to the animal.

One important factor is the condition of the mane and more particularly, the condition and appearance of the tail.

It has become recognized that a tail which appears initially to extend upwardly and which has a great deal of hair is a desirable factor which influences judges in awarding prizes in competitive shows, and is also of significance in the stud fees which stallions may command and the price at which mares may be sold.

It has therefore become the practice of breeders of horses, particularly Shetland ponies (to which this application refers in a generic sense) to emphasize the erectness and fullness of the tail of exhibition and show ponies. This has been done in the past largely by braiding into the natural hair of the pony's tail, hair of matching color derived from another animal. Various expedients have also been employed to cause the artificial portion of the tail adjacent the body of the pony to be held in a more or less upright position in order to enhance the general appearance of the pony. However, such devices as used in the past have been generally uncomfortable to the pony and resulted in sores due to chafing, and because of this discomfort the ponies were less tractable and sometimes showed tempermental and unwanted displays of irritation.

To overcome these deficiencies of the prior art devices, I have provided a simple, easily attached, and easily adjusted device for apparently maintaining the tail of a pony in an acceptably good form and conformation, without harming or irritating the pony.

It is thus an object of the invention to provide an improved supporting means for artificial additions of hair to the natural tail.

Other objects will become apparent from the following description, reference being had to the accompanying drawings in which

FIG. 1 is a side elevational view of a pony equipped with the improved artificial tail hair supporting means;

FIG. 2 is a perspective view of the artificial tail hair supporting means; and

FIG. 3 is a fragmentary sectional view, taken on the line 3—3 of FIG. 2.

In general, the harness in its simplest form, as used in pony judging contests and the like, comprises the customary bridle strappings 10 with a pair of reins 12 se-

2

cured to the bridle rings 14, as well as to the surcingle or belly band 16. A strap 26, buckled at one end to the belly band 16, is split at its rearward end into two end portions 22 which are buckled respectively to the forward ends of the crupper 20. As is customary, the crupper comprises a leather cover 28 around suitable padding and around one or more metal rods 30, the leather covering having buckles 32 at its ends for attachment to the straps 22.

10 Suitably conformed rods 34 are brazed to the rods 30 and are threaded at their outwardly extending ends to receive positioning nuts 36. These rods 34 are made of a deformable material such, for example, as a soft brass, so that they may be bent back and forth without fracture and act as supports for a hollow tubular artificial tail support element 38 which is conformed, as illustrated, to extend upwardly and rearwardly from the pony adjacent the base of the tail to provide a pair of inverted U-shaped portions 40 for support of the unnatural "toupee" or "wig" hair to supplement the natural hair of the tail.

15 The rods 34 may be bent to a certain degree to adjust the U-shaped portion 42 of the support, and its height may be adjusted further by proper positioning of the nuts 36 on the rods 34. It will be apparent that the nuts 36 form abutments against which the end portions of the support 38 rest, due to the weight of the support and the artificial tail carried thereby. Such adjustment is very easily accomplished so that the trainers and handlers may, within a very short time, adjust the pony's artificial tail 20 hair to a position providing the best presentation for judging or display.

25 Additional hair in a toupee-like assembly may be attached to support 38, as by a drawstring, such additional hair being interbraided, interlaced, or interwoven with the natural hair of the pony's tail, so as to provide the desired appearance of a full, bushy tail, and thus enhance the pony's appearance.

30 By use of this invention, the pony's actions during showing or judging will be normal because the support for the artificial tail hair does not chafe, and furthermore, does not result in sores. Also, the artificial tail support is readily adjustable to maintain the tail in a position which the trainer or handler believes will make the best impression upon the judges or prospective purchasers.

35 While I have shown and described a preferred embodiment of my invention, it will be apparent that numerous variations and modifications thereof may be made without departing from the underlying principles of the invention. I therefore desire, by the following claims, to include within the scope of the invention all such variations and modifications by which substantially the results of my invention may be obtained through the use of substantially the same or equivalent means.

40 I claim:

45 1. In a harness apparatus for a show pony or horse, the combination of a crupper having rigid members embedded in the sides thereof near the forward ends thereof, metal posts secured to and extending upward from said members on each side of said crupper, harness means for maintaining the crupper in position on the animal with the tail passing through the rearward portion of said crupper, an upstanding artificial tail supporting element having downwardly directed ends telescopically mounted to said posts ahead of the position of the tail, and means for adjustably limiting the telescopic

overlap of said ends and said posts to adjust the effective height of said supporting element.

2. The combination as set forth in claim 1 wherein said posts are formed of an easily bent metal resistant to fatigue.

3. The combination as set forth in claim 1 wherein said posts are threaded, said supporting element is tubular to provide ends to contain said posts, and said adjustable means comprises nuts threaded on said posts.
